ANGELO PERRI, OF HAVERHILL, MASSACHUSETTS, ASSIGNOR TO UNITED SHOE MACHINERY COMPANY, OF PATERSON, NEW JERSEY, A CORPORATION OF NEW JERSEY.

SHOE-FILLING MACHINE.

1,120,847.

Specification of Letters Patent. Patented Dec. 15, 1914.

Original application filed October 19, 1906. Serial No. 339,647. Divided and this application filed July 2, 1909. Serial No. 505,604.

To all whom it may concern:

Be it known that I, ANGELO PERRI, a citizen of the United States, residing at Haverhill, in the county of Essex and State 5 of Massachusetts, have invented certain Improvements in Shoe-Filling Machines, of which the following description, in connection with the accompanying drawings, is a specification, like reference character on 10 the drawings indicating like parts in the several figures.

This invention relates to machines for holding and delivering various materials. The invention which is adapted to a large 15 variety of uses is herein shown as embodied in a machine for filling shoes.

In the manufacture of shoes it is customary to mix ground cork, leather trimmings or other fine granular material with 20 a binder, which may or may not have the property of softening when heated, and to apply this mixture, known as a "filler", to the insole of a shoe between the inseams preparatory to laying the outer sole. The 25 present machine which comprises a receptacle and a relatively movable pressure applying member, herein shown as a piston, is adapted to hold and deliver material of this nature; and for convenience, the invention 30 will be described in connection with the particular machine shown.

In a device for filling shoes it is advantageous that an even and uniform pressure be maintained upon the filler particularly 25 when said filler is of a thick paste-like consistency; and inasmuch as the filler is not continuously discharged it is also advantageous that the pressure be yieldingly exerted so that during the intervals that the 40 outlet to the receptacle is closed the parts of the device may not be subjected to excessive strain. Accordingly, one object of this invention is to provide yielding means for producing relative movement between 45 the pressure applying member and the receptacle in order to force material from said receptacle, together with means for intermittently or periodically increasing the tension of said yielding means as said relative movement is continued. It will be apparent that by so constructing the device 50 that the intermittent or periodic actions of the tension increasing means are sufficiently frequent, the yielding means may be caused

to exert an approximately uniform pressure throughout the extent of the relative movement between the receptacle and the pressure applying member. Heretofore springs have been used to force material from receptacles but these springs have first 60 been compressed and then allowed to expand to their effective limit with the result that the pressure upon the material, instead of being uniform or constant, has decreased progressively so that the last of the material has been forced out by a pressure very 65 much less than that applied to the first of the material. In the present invention this disadvantage has been obviated by causing the spring to be compressed and expanded 70 within such narrow limits that the pressure which it exerts upon the material is nearly or approximately constant. Looking at the above feature of the invention from another standpoint it may be said to comprise 75 yielding means for producing the relative movement referred to above together with mechanism for increasing the tension of said yielding means to a predetermined extent after which said mechanism becomes 80 inoperative and remains so until the outlet to the receptacle is opened, a portion of the filler discharged and the tension of the yielding means somewhat reduced, whereupon the tension increasing means is again 85 thrown into operation. The machine may, therefore, be allowed safely to stand idle, the yielding means, however, remaining under sufficient tension so that as the outlet to the receptacle is opened and material 90 withdrawn the relative movement between said receptacle and the pressure applying member will be resumed and the tension increasing mechanism will take up its intermittent action once more. Any convenient 95 means for accomplishing this result may be employed, and in the illustrated embodiment a piston is advanced by a spring which is periodically compressed and allowed to expand, the compression being 100 brought about through the agency of a pulley which is caused to rotate intermittently.

As has been stated, the material which is used to fill insoles commonly consists of a mixture of solid particles with a viscous 105 binder. It is desirable that these ingredients be thoroughly commingled, and a further object of this invention relates to the

provision of a stirrer, the length of which is automatically accommodated to the changing space occupied by the filler as it is being expressed from the receptacle. This may conveniently be accomplished by providing an extensible stirrer attached at one end to the plunger, and at the other to a rotating part near the inner end wall of the receptacle so that as the plunger moves 10 from or toward said end wall the length of the stirrer increases or diminishes accordingly.

Where a filler, comprising a binder which has the property of softening upon the application of heat, is used, it is desirable to provide means for applying heat to said filler, and a further object of this invention is the provision of such means which, in the illustrated embodiment, takes the form of a 20 steam jacket surrounding the receptacle which contains the filler.

When heat is applied to the walls of a receptacle containing viscous material, the material adjacent the walls is liable to receive 25 an undue amount of heat and thereby to become burned or caked upon these walls. Accordingly, a further object of this invention relates to the provision of means whereby such burning or caking is prevented; and 30 in the illustrated embodiment this means takes the form of a continuously rotating scraper which traverses the inner surface of the walls of the receptacle.

These and other features of the invention 35 including certain details of construction and combinations of parts will be explained in connection with the following description of a machine and will be pointed out more definitely in the claims.

40 Referring now to the drawings:—Figure 1 is a vertical longitudinal section of a shoe filling machine with certain parts shown in dotted lines, and Fig. 2 is a section on line 3—3 of Fig. 1.

45 The machine comprises a receptacle provided with a valve and with controlling mechanism for said valve so constructed and arranged that by presenting a shoe in operative relation to the outlet to the receptacle, said valve is opened to allow filling material to flow upon the insole of said shoe. The mechanism for controlling the flow of material through the outlet and for pressing it against the insole will not be 50 further described here since it forms the subject matter of application Serial No. 339,647, of which the present application is a division.

55 Turning now to the dispensing apparatus, 60 a receptacle 1 provided with a filling opening closed by a cover 2 contains a piston which is adapted to be moved by mechanism, presently to be described, to express the filling material from the receptacle. 65 Surrounding the receptacle is a jacket 3

having an inlet 7 and an outlet 9 for the ingress and egress of a heating fluid.

Inasmuch as the filling material is liable to become burned or caked on the walls of the receptacle by reason of this heat, a 70 scraper 11 is provided, the arms of said scraper being mounted in slots 13 formed in a ring 15 which is rotatable on the piston 5. To prevent relative longitudinal movement between said ring and piston, these members 75 are formed respectively with an interengaging rib 17 and shoulder 19, and a plate 21 is fastened to said piston to hold said rib against said shoulder. With this construction the scraper may be rotated without affecting the movement of the piston. At its forward central portion this scraper is formed with a collar 23 which is fastened by a pin 25 to a shaft, said shaft having one end sustained in a bearing in the forward end of the receptacle and the other in a hollow rod 29 the function of which will presently be described. This shaft extends through the piston 5 and is rotated by 80 means of a pulley 31 and belt 33. 85

In order that the ingredients of the filling material may be kept thoroughly mixed, as well as to break up any lumps that may be formed, an extensible stirrer is provided. In the illustrated embodiment this stirrer 90 comprises a plurality of series of links 35 pivoted together, the ends of each series being also pivoted respectively to the ring 15 and to the forward end of the scraper 11, so that as the space occupied by the filling 95 material decreases the stirrer will gradually fold up, as shown in dotted lines in Fig. 1. 100

With the construction thus far described it will be clear that the stirrer and scraper may be continuously rotated without interfering in any way with the movement of the piston and that the stirrer is adapted to accommodate itself automatically to the varying space occupied by the filling material. 110

Turning now to the mechanism for producing an approximately constant pressure upon the filling material, the piston 5 is urged forward by a spring 37 which encircles the shaft 27 and is located between the rear wall of the piston and the forward end of the rod 29. In the operation of the device this spring is alternately compressed and allowed to expand so that by making the periodic compressions sufficiently frequent the pressure exerted by the spring can be made approximately constant. The mechanism for accomplishing this periodic compression comprises a plurality of parts which will now be described. The screw 115 threaded rod 29 is slidable in alined bearings in spider frames 65 and 77. Upon an extension of the hub of the spider frame 77 is mounted a loose pulley 30; and between said loose pulley and the spider 120 frame 125

130

frame 65 is mounted a driving pulley 32 which has a screw threaded bore to correspond with the screw threads on the rod 29, said second pulley being held from axial 5 movement as shown. A belt 93 connected with any suitable source of power is adapted to run on either pulley. It is clear then that by shifting the belt to the driving pulley the rod 29 will be advanced and the 10 spring 37 compressed. If now the belt be shifted from the driving pulley to the loose pulley the spring will be allowed to expand and force the piston forward; and thus by shifting the belt 93 back and forth from 15 loose pulley to the driving pulley the spring will be periodically compressed and allowed to expand. In order to cause the belt to be shifted automatically the following mechanism is provided. Rigidly fixed to the 20 screw threaded rod 29 is a collar 39, said collar having an upwardly extending bracket 41 provided with a pair of rolls 43 on each side thereof. The piston 5 carries a bracket 45 in which is rotatably 25 mounted a small shaft 47 to which are fixed two arms 49 and 51 at approximately right angles to each other. The arm 51 is forked and straddles the bracket 41, its forks extending between the rolls 43 on either side 30 of said bracket. Pivoted to the arm 49 is a link 53 which is loosely pivoted at its opposite end to a crank arm 55 which is fast to a shaft 57. This shaft is attached at one end to a bracket 59 on the piston 35 by means of a swivel connection 61 while the opposite end is slidably and rotatably mounted in a bearing block 63 which in turn is mounted in the spider frame 65. This shaft 57 carries a groove 67 which extends 40 nearly its entire length as shown. A second crank arm 69 carries in its hub a spline 71 which fits in the groove 67, so that the shaft 57 may be free to move with the piston 5. The outer end of the crank arm 69 is 45 loosely pivoted to a link 73 which slides through a bracket 75 fast to the second spider frame 77; and this link 73 is pivoted at its upper end to another link 79 which in turn is pivoted to the end of a crank arm 50 81. This crank arm is fast to a small shaft 83 rotatably mounted in a bracket 85 which is integral with the spider frame 77; and fast to the opposite end of this shaft is another crank arm 87 to the outer end of 55 which is loosely pivoted a belt shifter rod 89. This rod is slidable in a bearing 91, which is integral with the spider frame 65, and is adapted to shift the belt 93 from the loose pulley 30 to the driving pulley 32 and 60 vice versa.

The operation of the device is as follows:—The jacket 3 is connected with a source of steam or other suitable heating medium, the receptacle is filled with filling material and power is applied to the

belts 93 and 33. If then the mechanism is in the position shown in full lines in Fig. 2 with the belt 93 passing over the pulley 32, the rod 29 will be advanced and the spring 37 compressed. As the rod 29 moves 70 forward the rollers 43 will press against the end of the forked arm 51, thereby rotating the shaft 47 and depressing the end of the crank arm 55 and rotates the link 53. This in turn depresses the 75 shaft 57. The crank arm 69 is thus rotated and, through the links 73 and 79, the crank arm 81, the shaft 83 and the arm 87, moves the belt shifter 89 to the position shown in dotted lines with the belt shifted to the 80 loose pulley. At this moment the spring and the parts adjacent to it will occupy the relative positions shown in dotted lines at the right of the figure. The mechanism will now remain in approximately this position 85 until sufficient material has been removed by the presentation of shoes to the outlet to allow the spring 37 to expand until said spring and the parts adjacent to it occupy the relative positions shown in full lines. 90 During this expansion the movements of the link mechanism by which the belt 93 was shifted will be reversed, and the belt will be shifted from the loose to the driving pulley whereby the spring will be compressed once 95 more. It is thus apparent that the mechanism for advancing the piston is controlled by the removal of material from the receptacle, that the more frequent the periodic compressions of the spring, the more nearly 100 will a uniform pressure be exerted upon the material, and that said frequency can be controlled by properly positioning the parts of the belt shifting mechanism. As the piston is advanced the stirrer is contracted as 105 shown in dotted lines; at the same time the stirrer is rotated to thoroughly mix the ingredients of the filling material and the scraper prevents said material from becoming burned or caked upon the walls of the 110 receptacle.

It should be noted that the delivery of material from the receptacle is intermittent and that the periods between deliveries vary 115 in length. It should also be noted that since the outlet is opened by forcing the shoe between levers which are connected with a valve, the amount of material delivered at any given instant varies with the position which said shoe occupies. In order to promote brevity the word "irregular" will be used to characterize this delivery it being understood that the word is intended to cover either of the conditions set forth above.

The invention having thus been described, what is claimed as new and desired to be secured by Letters Patent is:

1. The combination of a receptacle, a piston, means for moving said piston along 130

- said receptacle, and means controlled by the piston during its movement for controlling the operation of the piston moving means.
2. The combination of a receptacle, a piston, means for advancing the piston, a threaded shaft for operating the piston advancing means, a nut engaging the threaded shaft, and automatic means for intermittently rotating one of said parts.
- 10 3. The combination with a receptacle for material of a pressure applying member, yielding means for producing relative movement between said member and receptacle, and automatic means for intermittently increasing the tension of said yielding means as said relative movement is continued.
4. A machine of the class described, having in combination, a receptacle provided with an outlet, a piston, a spring for advancing said piston, means for compressing said spring, and means whereby the compressing means periodically comes to rest.
- 20 5. A machine of the class described, having in combination, a receptacle provided with an outlet, a piston, resilient means for advancing said piston, and automatic means for compressing the resilient means.
- 30 6. A machine of the class described, having in combination, a receptacle for material, said receptacle being provided with an outlet, a piston, a spring for advancing said piston, means for compressing said spring, and means whereby said compressing means becomes operative by removal of a quantity of material from said receptacle.
- 35 7. A machine of the class described, having in combination, a receptacle for material, said receptacle being provided with an outlet, a piston, resilient means for advancing said piston, and means automatically actuated on removal of a quantity of material to create tension in said resilient means.
- 40 8. A machine of the class described having in combination a receptacle provided with an outlet, a piston therein, a compressing member, a spring interposed between said member and piston for advancing the latter and automatic means for advancing said member when said member and piston have been separated to a predetermined distance.
- 45 9. A machine of the class described having in combination a receptacle having a discharge opening, a piston fitted therein, a spring normally acting to move said piston toward said opening, and automatic means for increasing the tension of said spring, as the piston is advanced.
- 50 10. A machine of the class described having in combination a receptacle having a discharge opening, a piston fitted therein, an adjusting screw, a spring interposed between said screw and said piston for forcing the latter toward said opening, and means for automatically advancing said screw when
- said screw and piston have been separated to a predetermined extent.
11. An apparatus of the class described having in combination a receptacle from which material is delivered irregularly, and automatic means including a spring constructed and arranged to maintain an approximately uniform pressure upon said material.
12. The combination of a receptacle, a piston, means for moving said piston along said receptacle, and means responsive to the forward movement of the piston for controlling the operation of the piston moving means.
13. In apparatus of the class described, the combination with a receptacle of a pressure applying member for forcing material from said receptacle, a spring for advancing said member, and intermittently operating mechanism for compressing said spring, the operation of said member being automatically controlled in accordance with the tension of said spring.
14. In apparatus of the class described, the combination with a receptacle of means for maintaining material contained in said receptacle under pressure, comprising a movable pressure applying member, a spring for advancing said member, mechanically actuated mechanism for compressing said spring, and actuating devices responsive to the degree of tension of the spring for rendering said mechanism operative or inoperative.
15. In apparatus of the class described, a receptacle, a movable pressure applying member, a spring, mechanism for creating tension in said spring, and means set into operation as the spring reaches predetermined limits of minimum and maximum tension for rendering said mechanism operative or inoperative.
16. In apparatus for delivering material, the combination of a receptacle from which the material is delivered irregularly, of intermittently actuated mechanical devices, the operation of which is controlled automatically by the discharge of the material, constructed and arranged to maintain upon the material a pressure variable only within predetermined limits.
17. The combination of a receptacle having an outlet, means for forcing material from said receptacle, an extensible stirrer, and means for operating said stirrer.
18. The combination of a receptacle having an outlet, a piston in said receptacle and a stirrer located between said piston and said outlet, said stirrer being capable of folding as said piston is advanced.
19. A dispensing apparatus, having in combination, a receptacle provided with a discharge opening, a piston in said receptacle, means for advancing said piston toward said

opening, means for stirring the material contained in said receptacle, said stirring means automatically contracting as said piston is advanced, and means for actuating said stirring means.

20. A dispensing apparatus comprising a receptacle having a discharge opening, a piston fitted therein, means for moving said piston toward said opening, an extensible stirrer having a swivel connection with said piston, and means for rotating the stirrer.

21. A dispensing apparatus comprising a closed cylindrical receptacle having a discharge opening at one end, a two part piston therein, one part being rotatable with relation to the other, means for forcing said piston toward said opening, a stirrer frame rotatably mounted in said receptacle between said piston and said opening and connected at one end to the rotatable member of the piston, and means for rotating said stirrer.

22. A dispensing apparatus comprising a receptacle having a discharge opening, a piston fitted therein, means for moving said piston toward said opening, an extensible stirrer connected to said piston adapted to

be contracted as the piston is advanced and means for rotating said stirrer.

23. The combination with a receptacle for material and means for forcing material therefrom said receptacle being provided with a jacket for a heating fluid, of means for preventing said material from caking upon the walls of said receptacle.

24. A machine of the class described, having, in combination, a receptacle having an outlet, said receptacle being provided with a steam jacket, a piston in said receptacle and a scraper having arms adapted to traverse the inner wall of said receptacle.

25. The combination of a receptacle, a piston, means for moving said piston forward in said receptacle, and means controlled by the piston in its movement for causing further forward movement of the piston moving means.

In testimony whereof I have signed my name to this specification in the presence of two subscribing witnesses.

ANGELO PERRI.
